SILAS C. SALISBURY, OF NEW YORK, N. Y.

Letters Patent No. 88,080, dated March 23, 1869.

IMPROVEMENT IN FURNACES FOR UPRIGHT STEAM-GENERATORS.

The Schedule referred to in these Letters Patent and making part of the same.

To all whom it may concern:

Be it known that I, SILAS C. SALISBURY, of the city of New York, in the county of New York, and State of New York, have invented certain new and useful Improvements in Furnaces for the Combustion of Fuel, and in their Application to Vertical Steam-Boilers; and I do hereby declare that the following is a full, clear, and exact description thereof, and of their mode, or manner of operation, reference being had to the accompanying drawings, and to the letters of reference marked thereon, and making a part of this specification.

The object of my invention is to economize the use of fuel for generating steam, and to make the same effectual to the greatest degree possible; and

The nature of my invention consists in the construction and arrangement of the fire and combustion-chambers of steam-generators, whereby to secure a better combustion of the fuel; and this I accomplish by mechanical devices which produce chemical affinities, which act in harmony with each other.

It is a well-known fact that with the present construction and arrangement of furnaces, the combustion of all kinds of fuel is very imperfect, not more than about thirty per cent. of the heat-power of the fuel used being actually made effective, the balance passing off in the form of carbonic oxides, (which are also injurious to the flues, &c., through which they pass,) or as particles of unconsumed products of combustion, or partially consumed.

Various attempts have been made to secure more nearly perfect combustion, and thus economize fuel, and with some success, but such efforts have been only in a limited degree successful.

My invention consists—

First, in the construction and arrangement of the fire-chamber, or what may be called the preparing-chamber, or retort, in which the fuel is placed, and where it is slowly decarbonized, and which chamber is abundantly supplied with oxygen and hydro-oxygen gases; and

Second, in the combination therewith of a combustion-chamber, into which the carbonic oxides and other products of combustion, as formed in the fire-chamber, pass through numerous small orifices, or perforations, and are thus subdivided into many currents, or parts, and where, by means of highly-heated air, and decomposed steam, constantly supplied to such combustion-chamber, such carbonic oxides are changed in character, and the gases of the coal, air, and water are perfectly mixed and combined, both mechanically and chemically, so that everything combustible is consumed, and a very intensified heat produced, and with a comparatively slow combustion of fuel.

From a long series of experiments, carefully and practically made, I have demonstrated that by the use of my invention and improvements, a saving of a very large per cent. of fuel is effected, whether anthracite or bituminous coal or wood is used.

The drawings show the construction of my invention with a vertical boiler.

Figure 1 is a perspective view of a vertical steam-generator constructed with my invention.

Figure 2 is a vertical section of the same.

Figure 3 is a horizontal section through the lower part of the fire-chamber.

Figure 4 is a view, partly perspective and partly in vertical section, of the fire-chamber.

Figure 5 is a bottom view of the entire furnace and grate.

Figure 6 is a representation of a detached portion of the outer, or iron lining of the fire-chamber.

The grate, A, is made of very considerable depth, or thickness, and is formed with abundant and numerous openings, or air-passages, a, so as both to allow large quantities of air to pass into the fire from below, and also divide the air so admitted into numerous and small currents.

The air thus supplied to the fire-chamber becomes more or less heated by passing through the openings a, but it at the same time keeps the under surface of the grate comparatively cool, and thus makes it more durable.

When the grate is a circular, or tilting grate, as shown in the drawing, the enclosing-surface, or plate A', should also be fitted with openings, b, so as to insure the admission of air from below to every part of the bottom of the fire or burning fuel.

The fire, or preparing-chamber C is constructed substantially as follows:

A heavy plate or piece of cast-iron, B, about half an inch to an inch in thickness, is placed within and against the inner plate, c, of the boiler, and extends around the fire-chamber, and upward about as far as the perpendicular sides of such chamber.

On the inner side of such cast-plate B, or made a part of it, is placed, at regular or suitable intervals, say every two inches, a series of pipes, or half-round tubes, d, which are open at the bottom to freely take in air, and closed at the top to prevent the air passing through them, but having, along their inner sides, a series of perforations, e, to allow the air to pass out from such tubes horizontally.

A section of one of such tubes d, open at the bottom and closed at the top, is shown in figs. 2 and 6.

Within such cast plate B, and in contact with such air-tubes d, is laid or placed the fire-brick lining f, which makes the inner walls of the furnace proper, the inside surface of such fire-brick being formed with flutes, or concave recesses, so as to prevent the coal or fuel packing against the sides of the furnace; and through such fire-brick, all around the fire-chamber, are made holes, g, for the passage or admission of air, corresponding in position with the perforations e in the tubes d.

By means of such air-supplying tubes d, perforated as described, and the corresponding perforations g, through the fire-brick lining f, air is continually sup-

plied to the fire, or preparing-chamber C, and enters such chamber in small jets on every side of the burning fuel, both at or near the top thereof, and also at different points below.

Large quantities of air are thus not only constantly supplied to the chamber C, but by means of such arrangement of perforated tubes and fire-brick, in combination with the grate, such air is presented to and distributed through every part of the burning fuel.

The air supplied to the chamber C through the tubes d, also becomes highly heated by passing along the heated surface of the cast-iron plate B, and its tubes d, and through the heated fire-brick lining, and the fire-chamber is thus, in fact, continually supplied with a hot-blast; and to assist in heating the air so supplied to the chamber C, the tubes d may be filled with fine gauze cloth, made of asbestos, which, though continually hot, will not be consumed.

To such chamber C there is also admitted, through or by means of a pipe, h, extending underneath the open mouths of the air-tubes d, and opening into the same by means of small perforations, or jets, steam or superheated steam, taken from the boiler or any convenient or suitable source, which becomes decomposed in passing into or on entering such chamber, furnishing additional oxygen and also hydrogen, and thereby assisting to effect a more complete and perfect combustion of the fuel.

By thus supplying the fire, or preparing-chamber, on every side thereof, and on the top of and at different points of the burning fuel, with divided jets of heated air and of decomposed or decomposing steam, the decarbonization of the fuel commences, or is carried on from the top and from the outside of the furnace, instead of from the bottom, and, at the same time, the intense heat penetrates the centre, and completely effects the same results there. The combustion being thus carried on most actively from the top and sides of the fire, the under surface of the grate-bars, notwithstanding the great intensity of the fire, remains quite cool, comparatively. In an ordinary furnace, with a fire of the intensity easily and constantly maintained in my fire, or preparing-chamber, the grate-bars would be melted or burned out in a very short time.

The quantity of air and steam supplied to the chamber C, through the tubes d, may be regulated and varied by means of a sliding plate, D, so arranged that the supply of air and steam, entering the tubes d, can be partially or wholly cut off, as desired, and the consumption of the fuel can thus be regulated according to circumstances.

The fire, or preparing-chamber C, is wholly arched over, as shown in figs. 2 and 4, with fire-brick, or some material capable of bearing a very intense heat without injury; and above or outside, is what I call the combustion-chamber E.

Communication between these two chambers, or from the fire to the combustion-chamber, is solely through or by means of numerous small openings j. The carbonic oxides and products of combustion formed in the fire, or preparing-chamber C, in passing through such openings into the combustion-chamber E, are divided into small currents, and enter such chamber E at many different angles, and thus are caused to come in more complete and intimate contact with, and are thus more effectually mixed with the jets or currents of heated air and steam which enter such combustion-chamber, as well as the fire, or preparing-chamber C.

Such supplies of air and steam are furnished to the combustion-chamber E, through the spaces, or openings l, formed by the cast-iron plate B on the one side, and the fire-brick f on the other, and the air-tubes d, before described as supplying air and steam to the fire-chamber C. A section of one of such openings, or

spaces l, open at the top to allow the air and steam to pass through it and into the combustion-chamber E, is shown in figs. 2 and 4. As before described, in connection with the fire-chamber C, the air supplied to the combustion-chamber becomes highly heated in passing thereto, and is, in fact, a continuous hot-air blast.

The steam-jets, supplied by the pipe h and furnished to the combustion-chamber, become wholly, or to a very great degree, decomposed, by contact with the highly-heated iron plate B and fire-brick f, and produce hydro-oxygen gases, and thereby increase the quantity of oxygen, and intensify the heat in both the chambers E and C.

The air, becoming highly heated while passing to the combustion-chamber, is rendered lighter than the carbonic oxides continually pouring into such chamber from the fire-chamber C, and an immediate chemical union and utilization of such gases of coal, air, and steam, takes place, and their complete and perfect combustion is produced.

The pressure and velocity of the steam escaping upward from the pipe h, also produce or cause an increased draught, and consequently an increased amount of oxygen is carried in through the tubes d for combustion. Actual practical tests prove that such use of steam in the chambers E and C adds greatly to the economy produced or effected by the general combination.

The quantity of air and steam supplied to such combustion-chamber E will also be governed and regulated by a sliding plate, as before described in connection with the fire-chamber.

The arch of the chamber C may spring directly from the fire-bricks f, within the line or circuit of the spaces, or openings l l, or, if extending over the line of such openings, has open spaces in it, to allow the air and steam to pass freely through the spaces l into the combustion-chamber. The orifices j, in the top and sides of the chamber C, should be about half an inch in diameter, or of about that capacity.

To secure greater strength and durability, as well as a saving of expense, I prefer to make the fire-bricks f, forming the fire-chamber proper, in a solid ring or piece; and as before set forth, to prevent the fuel packing against the sides of such inner clay ring, as well as to prevent the openings g thereon getting filled and becoming stopped up, the inner surface of such clay lining is fluted, or recessed, as shown in figs. 3, 4, and 5.

The heat and products of combustion pass from the combustion-chamber E up through the hot-air tubes F, which are surrounded by water, and into the chamber G, and thence off through the chimney or smoke-pipe H, which may be provided with a damper, as in ordinary cases.

What I claim as my invention, and desire to secure by Letters Patent, is—

1. The construction of the sides of the fire, or preparing-chamber with double, or outer and inner walls, and with tubes and air-passages between them, for the supply and heating of the air, substantially as set forth.

2. The construction and arrangement of the perforated air-tubes d, for supplying air to the fire, or preparing-chamber, and in combination therewith, the perforated inside lining, or wall of such chamber, whereby the air is delivered to the fuel in numerous or divided jets, on every side of such chamber, and on the top of and at different points in the burning mass, substantially as set forth.

3. The construction of the fire, or preparing-chamber, with a continuous arch or top, perforated with numerous holes, or openings, substantially as set forth.

4. The combination, with the fire-chamber C, constructed as described, of the outer combustion-cham-

ber E, such outer chamber being also separately supplied with heated air and steam, substantially as herein set forth.

5. The construction and arrangement of the double walls of the preparing-chamber, and the arrangement of the air-tubes and passages between such walls, whereby air or air and steam can be supplied at the same time to the fuel-chamber, and to the outer or combustion-chamber, substantially as herein described.

6. The arrangement of the tubes, or passages for supplying air to the fire and combustion-chambers, with the perforated steam-pipe, for supplying com-

mingled steam and air to such chambers, as herein set forth.

7. The construction and arrangement of the air and steam-supplying tubes and pipes and the movable plate for governing and regulating the supply of air and steam, as set forth.

8. The combination, with the vertical boiler, of the fire, or preparing-chamber and combustion-chamber, constructed and arranged substantially as described.
